UNITED STATES PATENT OFFICE.

CLARENCE F. KUNYE, OF BROOKFIELD, WISCONSIN, ASSIGNOR TO FEDERAL STEEL SASH COMPANY, OF WAUKESHA, WISCONSIN, A CORPORATION OF WISCONSIN.

WINDOW SASH.

Application filed December 8, 1926. Serial No. 153,328.

- The invention relates to window sash, and more particularly to fabricated or welded steel sash having a ventilator section.
- The object of the invention is to provide a hinge connection between the swinging ventilator section and the sash frame whereby the ventilator section swings on the sash frame itself and the use of special hinges is obviated.
- 10 A further object of the invention is to provide a sash construction in which the swinging ventilator section pivots on the sash frame itself and has weathering contact therewith.
- 15 The invention further consists in the several features hereinafter set forth and more particularly defined by the claims at the conclusion hereof.
- In the drawings Fig. 1 is a detail front 20 elevation view of a window sash embodying the invention, parts being broken away and parts being shown in section;
- Fig. 2 is a front elevation view of parts of the sash during assembly to illustrate 25 the manner in which the ventilator section is inserted into the sash frame;
- Fig. 3 is a detail sectional view taken through the sash on the line 3—3 of Fig. 1, parts being broken away;
- 30 Fig. 4 is a vertical sectional view taken on the line 4—4 of Fig. 2;
- Fig. 5 is a detail sectional view taken on the line 5—5 of Fig. 1.
- Referring to Figs. 1 and 3, the numeral 6 35 designates the fixed frame section of the sash and it will be noted from Figs. 3 and 5 that this frame consists of side and end T-bars which may be welded or otherwise suitably secured together at the corners so 40 as to form a frame. An angle bar 7 is welded or otherwise suitably secured in each instance to the web 8 of the end or transversely extending T-bars of the frame and angle bars 9 are detachably secured by 45 screws 10, or other suitable fastening means, to the webs 11 of the T-bars forming the sides of the sash frame.
- The ventilator section 12 is formed by
- T-bars 13 joined, as by welding, at their lower ends to a transverse T-bar 14 and at 50 their upper ends to an angle bar 15, which angle bar also has one of the legs of a smaller angle bar 16 welded or otherwise suitably secured thereto.
- The inwardly extending flanges 17 of the 55 T-bars forming the side portions of the frame 6 have flat faced notches 18 formed therein and it is upon the bottom of these notches that the ventilator section 12 is free to pivot or swing relative to the fixed frame 60 of the sash, it being noted that when the ventilator section is in assembled position those portions of the leg 19 of the bar 15 projecting over the flanges 17 engage the lower sides of notches 18 and may be turned 65 or swung thereon to the position shown in dotted lines in Fig. 3 or to a position at right angles to the plane of the sash if a full opening is desired, any of the well known connections between the ventilator 70 sash section and the main sash frame being used to hold the ventilator section in full or partially open position.
- When the parts are in closed position it 75 will be noted from Figs. 3 and 5 that an efficient weathering contact is secured since the upwardly extending leg of the angle bar 16 abuts against the flange 20 of the transverse bar of the frame 6, the flange 21 of the bar 14 abuts against the flange 22 of the 80 lower transverse bar of the frame 6, the ends of laterally extending webs or flanges of the bars 15 and 14 abut against the angle bars 7, the ends of webs of the bars 13 abut 85 against the flanges 23 of the side bars 9 of the frame 6 and the flanges 24 of the bars 13 abut against the flanges 17. Furthermore, the upwardly extending leg of the bar 16 covers the slots 18, as shown in Figs. 1 and 3.
- In assembling the ventilator section in the 90 main frame the bars 9 are removed and then by sliding the ventilator section in from the back toward the front, as indicated by the arrow 25, with one of the flanges of the side bars 13 sliding on the lower side of the

notches 18, the ventilator section is moved to a position where it may be turned downwardly to the position shown in Fig. 3 with the bar 16 then disposed in the channel 5 formed between the upper T-bar of the frame 6 and the upper bar 7, after which the bars 9 are secured to the webs 11 in any suitable manner, as by the screws 10, it being noted that the base portions 26 of the bars 10 9 terminate at a distance from the upper end of the flanges 27 of said bars so as not to interfere with the free turning movement of the ventilator section.

The ventilator section is usually provided 15 with window-light sections and one of the muntin bars 28 for these sections is partly shown.

It will, of course, be understood that the main sash frame may be extended above and 20 below the ventilator section and be provided with window-light sections, and may also have window-light sections at the sides of the ventilator section, but since the invention resides in the hinge connections between 25 the ventilator section and that portion of the main frame surrounding the ventilator section, and to which it is attached, further showing of variations in the main frame itself are deemed unnecessary.

30 I desire it to be understood that this invention is not to be limited to any particular form or arrangement of parts except in so far as such limitations are specified in the claims.

35 What I claim as my invention is:

1. In a window sash, the combination with a main frame having parts forming a ventilator opening with sides and ends channel-shaped in cross section, a ventilator comprising 40 a frame having T-bars at its sides and at its lower end portion, and oppositely disposed angle bars at its upper end portion, one of said last-named angle bars being offset inwardly from the other angle bar, 45 and means adjacent the upper end portion of the ventilator forming a pivotal connection between the ventilator section and the main frame whereby the ventilator section swings on a part of said main frame, the webs of said T-bars having weathering contact 50 with one side of the channel section of the main frame and the flanges of said T-bars having weathering contact with the other side of the channel section of the main frame, the offset angle bar also having weathering contact with one of the sides of 55 the channel section of the main frame.

2. In a window sash, the combination of a marginal frame for a ventilator section having spaced inwardly extending flanges at the sides of said frame adjacent the top having notches formed therein, a ventilator section having flanges working in said notches and engageable with said spaced flanges to form a double weathering contact 60

throughout the entire opening in the marginal frame, and flanges mounted in said notches and turnable thereon to swing the ventilator section relative to the marginal frame.

3. In a window sash, the combination of a rigid marginal frame for a ventilator opening having detachable side frame members associated therewith, of a ventilator section insertable in said frame on the removal of 70 said side frame members and pivoting on said frame, and means for securing said side frame members to said frame, the attachment of said side frame members to said frame preventing the removal of said ventilator section therefrom.

4. In a window sash, the combination of a marginal frame for a ventilator opening providing side and end channels, the side channels including angle bars, means for detachably securing said angle bars to said frame, and a ventilator section hinged to the fixed parts of said side channels to said marginal frame and having parts in weathering contact with the sides of the channels, said ventilator section being insertable into operative position in said frame on the removal of said bars and being secured therein against removal on the attachment of said bars.

5. In a window sash, the combination with a main frame having parts forming a ventilator opening with sides and ends provided with spaced inwardly-extending flanges and notches in one of the flanges on each side of the frame adjacent the top portion thereof, a ventilator comprising a frame having angled bars at its sides and at its lower end portion, said bars having their flanges in contact with the front flanges of said sides and lower end portion and their legs in contact with the back flanges of said sides and lower end portion, said ventilator frame also including oppositely disposed angle bars at its upper end portion, one of which engages 105 in said notches to form a pivotal connection between the frames, one of said last-named angle bars being offset inwardly from the other angle bar whereby said oppositely disposed bars provide a double weathering contact 110 with the sides of the channel section of the upper end portion of the frame.

6. In a window sash, the combination of a marginal frame having spaced, inwardly extending flanges forming a channeled frame, there being notches formed in one of the flanges at the sides of the frame adjacent the upper end thereof, the other one of the flanges at the sides of the frame terminating below these notches, a ventilator frame comprising side and lower end T-bars with their legs respectively engaging one set of flanges of the marginal frame and their flanges abutting the other set of flanges of 120 said marginal frame, said ventilator frame 125

also including oppositely disposed angle bars forming the upper end portion of its frame, one of which angle bars is offset rearwardly from the front of the other, and 5 works between the spaced flanges of the upper end of the main frame and has an upstanding leg abutting against the inner

side of the forward flange of said marginal frame and covers the openings formed by said notches, the other of which has weathering contact with the other flange at the upper end of the marginal frame. 10

In testimony whereof, I affix my signature.
CLARENCE F. KUNEY.
